UNITED STATES PATENT OFFICE

ROBERT G. ANDERSON, OF ELMHURST, NEW YORK, ASSIGNOR TO INTERNATIONAL MOTOR COMPANY, OF NEW YORK, N. Y., A CORPORATION OF DELAWARE

BODY-BOLSTER CONSTRUCTION

Application filed August 13, 1927. Serial No. 212,625.

The present invention relates to railway car construction and deals particularly with cars which are designed to carry a power generating unit as well as the driving units, 5 which, in this particular instance, are the driving motors carried upon the trucks.

More particularly, the invention relates to a construction which is designed to serve as a rigid base upon which the power units are 10 mounted. In this case the sub-structure of the car, is such as to provide a unitary base having bearing points which are capable of carrying the weight of the power generating units in addition to serving as the usual bracing structure for the car body.

An object of the invention therefore, is to provide a body bolster construction which reduces the weight of the car to a minimum and yet serves to impart great strength and 20 rigidity to the body to the car.

A further object of the invention is to provide a mounting for the power generating units to be carried upon a rail car, the mounting being in effect, a unitary and rigid 25 base, having bearing points over the body bolster which are designed to carry the weight of the units.

Further and other objects of the invention will appear as the description proceeds 30 and reference will now be had to the accompanying drawings forming a part hereof for a more detailed description of the invention, wherein:

Figure 1 is a plan view, partly broken 35 away, and showing the body construction embodied in the present invention, the bolsters and center sill being shown in dotted lines.

Figure 2 is a section taken on line 2—2 40 of Figure 1 and looking in the direction of the arrows.

Referring to the accompanying drawings, 45 a designates a unitary floor or base plate which serves as the base upon which the power units are to be mounted. This floor section is unitary in so far as a certain section of the car embodied is concerned, the adjoining floor being represented by abutting section a' . Through the center of the car, the center sill b extends, it being composed of side

channels b' secured together in any suitable manner. The body bolsters are represented by the reference character c . These bolsters are fabricated from plates of metal c' extending from either side of the center sill to the 55 side of the car and being riveted to the unitary floor plate a , as well as the channel members b' . The body bolsters c are spaced with respect to the floor plate so that the power units to be mounted thereon can be placed 60 upon the body bolsters. This is illustrated in Figure 1, wherein d are channels forming the bed plate of the power units, and d' are the bearing blocks, supporting the weight of the units and resting over the body bolsters c .

Across the under sides of the body bolsters and center sill are fastening plates e . These plates extend from side to side of the car and are riveted to the plates c' and center sill channels b' . Between the center sill channels b' , a plate c^2 is secured, thus completing the 70 bolster strength for that section of the car. At the sides of the car, and over the ends of the floor plate a and bolster sections c' , are side plates f . These plates are formed as 75 angles, and riveted to the respective elements.

Figure 2 shows the units mounted on the channels d which carry the weights thereof and rest upon the floor plate a over the body bolsters c , the pedestals d' serving to receive 80 the weight of the respective units, and at the same time securing them in position.

It will be apparent, from the above description, that the unitary base section provided by the above construction will be of a highly 85 rigid character as well as being extremely strong. The weight of the resulting structure is reduced to a minimum without sacrificing any of the strength and rigidity required for a completely satisfactory base 90 for the power units carried on the car. The specific design and construction of the body bolsters and co-operating structure may be varied and the invention is not to be limited 95 save as defined in the appended claims.

While the present invention is especially concerned with the portion of the underframe over the trucks which transmits the load thereto, it is by no means limited to such construction, but may be made use of at any 100

section intermediate the ends of the car, i.e., not directly over the trucks or supported thereon.

What I claim is:

- 5 1. A body construction for a rail car comprising a center sill, spaced body bolsters connected thereto comprising sections riveted to the center sill at either sides thereof and between the sill sections, a unitary floor plate secured to the body bolsters and the center sill, end plates secured over the floor plate and the ends of the bolsters, and a facing plate secured under the bolsters and running the entire length thereof.
- 10 2. A body construction for a rail car comprising a center sill, spaced body bolsters connected thereto comprising sections riveted to the center sill at either sides thereof and between the sill sections, a unitary floor plate secured to the body bolsters and the center sill, end plates secured over the floor plate and the ends of the bolsters, means to secure power units to the floor plate over the bolster sections, and a facing plate secured under the bolsters and running the entire length thereof.
- 15 3. A body construction for a rail car comprising a center sill and flooring carried thereby, bolsters secured thereto in spaced relation adjacent one end thereof, an independent section of said flooring secured to the sill and bolsters, and means to secure power units upon the independent section over the bolsters.
- 20 35 This specification signed this 10th day of August A. D. 1927.
